(57) **CLAIM**

The ornamental design for a vehicle rear taillamp, as shown and described.

DESCRIPTION

FIG. 1 is a perspective view of a vehicle rear taillamp;

FIG. 2 is a front view of the vehicle rear taillamp;

FIG. 3 is a side view of the vehicle rear taillamp; and,

FIG. 4 is a top view of the vehicle rear taillamp.

The broken lines shown in the figures are included for the purpose of illustrating portions of the vehicle rear taillamp and form no part of the claimed design.
